United States Patent Office

Des. 185,537
Patented June 23, 1959

185,537

CHAIN LINK

William H. Devonshire, Williamsville, and Edward R. Behnke, Lockport, N.Y., assignors to Columbus McKinnon Chain Corporation, Tonawanda, N.Y.

Application February 13, 1957, Serial No. 44,854

Term of patent 14 years

(Cl. D54—3)

Fig. 1.

Fig. 2.

Fig. 3.

Fig. 1 is a top plan view of a chain link, showing our new design;

Fig. 2 is a side elevational view thereof; and
Fig. 3 is an end elevational view thereof.

The side not shown is identical with that shown in Fig. 1. The essential features of our design reside in those portions shown in full lines.

We claim:

The ornamental design for a chain link, substantially as shown and described.
